DESULFURIZATION OF LIGHT OILS WITH
HYDROGEN FLUORIDE-ACTIVATED ALU-
MINAArthur P. Lien, Highland, and Harold Shalit, East
Chicago, Ind., assignors to Standard Oil Com-
pany, Chicago, Ill., a corporation of Indiana

Application November 17, 1951, Serial No. 256,868

5 Claims. (Cl. 196—28)

1

This invention relates to the desulfurization of light oils with alumina which has been activated with hydrogen fluoride. More particularly, it relates to the desulfurization of a high sulfur olefinic naphtha such as coke still naphtha by a combination process which involves treating the high sulfur olefinic naphtha with hydrogen fluoride to obtain a raffinate, defluorinating the raffinate and then contacting the defluorinated raffinate with HF-activated alumina under conditions to obtain high yields of highly olefinic low sulfur gasoline.

It is known that gas oils which are higher boiling than naphtha may be extracted with HF prior to catalytic cracking in order to obtain desulfurization and to improve the effectiveness of the cracking operation (U. S. 2,525,812-3). It has also been proposed to effect HF alkylation of an alkylatable material with an alkylating material, at least one of which is in the gas oil boiling range, and to catalytically crack the resulting alkylate with silica-alumina catalyst (U. S. 2,434,623). Such processes were not applicable to olefinic charging stocks of the naphtha boiling range because excessive amounts of gasoline were lost in the extract and the initial HF treatment produced large amounts of alkyl fluorides and olefin polymers, as well as alkylates. An object of our invention is to provide a process wherein the initial HF treatment of high sulfur olefinic naphtha will be advantageous rather than disadvantageous, and to provide an improved method and means for processing the raffinate product produced in the HF treating step. A further object is to provide an improved desulfurization process employing a relatively inexpensive catalyst which can be activated by alkyl fluoride contaminants in charging stock undergoing treatment.

An important object is to desulfurize a high sulfur olefinic naphtha by a combination of steps to obtain a higher yield of a more highly olefinic naphtha product which is lower in sulfur content and higher in octane number than could be attained by processes heretofore known to the art. Hydrodesulfurization, for example, is not only an expensive process but it results in undue saturation of olefins. Solvent extraction, acid treating, and many other types of processes have been proposed for effecting desulfurization of coke still naphtha but none of the prior proposals have given the desired product yield-quality relationship without unduly large operating costs. Another object of our invention is to attain such desired product yield-quality

2

relationship at low cost. Other objects will be apparent as the detailed description of our invention proceeds.

The invention is applicable to high sulfur olefinic naphthas generally, i. e. to naphthas in which the olefin to paraffin ratio is in the range of about 3:1 to 1:3, and it is particularly advantageous for charging stocks in which the olefinic content exceeds the paraffinic content. 5 By "high sulfur" we mean a sulfur content which is at least about .25 weight percent and which is usually in the range of about 0.3 to 3 weight percent. By "naphtha" we mean a normally liquid hydrocarbon fraction boiling below 450° F. and usually boiling almost entirely within the range of 100° to 400° F. An outstanding example of a high sulfur olefinic naphtha is the naphtha produced by the coking of high sulfur reduced crude in any known manner, such, for example, as by continuously introducing heated charging stock into a coke drum at about atmospheric pressure to 50 p. s. i. g., at a temperature in the range of about 850° to 950° F. and continuing the operating until coke solidifies 10 in the drum, the vaporous products from the drum being fractionated into a coke still naphtha fraction and one or more heavier fractions. While our invention is applicable to high sulfur olefinic naphthas produced by thermal cracking or by catalytic cracking, its outstanding advantage is in the refining of coke still naphtha because this charging stock is the most difficult of all to desulfurize or otherwise refine by conventional methods.

15 In accordance with our invention, a high sulfur olefinic naphtha is contacted with hydrogen fluoride at a temperature lower than that heretofore employed for extraction of gas oil; the preferred contacting temperature is in the range of about 30° F. to 30° F., or about —20° F. With higher contacting temperatures excessive valuable gasoline components are lost to the extract. The amount of HF, based on charging stock, should be in the range of about 5 to 200 volume percent, 20 and preferably in the range of 10 to 100 volume percent. The pressure should be sufficient to maintain the system in liquid state and the time of contact should be in the range of 6 to 60 minutes, e. g. about 30 minutes. Under such conditions only about 10 to 15 percent of the charging stock is removed as extract and about 30 to 25 40 percent of the initial charge is converted by polymerization and alkylation to materials of the gas oil boiling range.

55 The total raffinate from the initial HF treat-

ing step is then contacted with alumina at a superatmospheric pressure which is preferably in the range of about 50 to 500 p. s. i. g. or more, with a space velocity in the range of about .1 to 3, e. g. about 1, and at a temperature in the range of about 600 to 900° F., e. g. about 750° F. Under these conditions the raffinate is defluorinated and the alumina becomes activated by the released HF which it absorbs. The gas oil boiling range components of the charging stock are depolymerized and dealkylated, additional desulfurization is effected, and gas and coke formation are remarkably small, indicating that cracking takes place only to a very minor extent. The total product from this alumina treating step is characterized by a sulfur content of only about .04 weight percent and a fluorine content of the order of .001 weight percent or less. The naphtha boiling range portion of the product amounts to about 75 to 80 percent of the initial high sulfur naphtha and it is characterized by a sulfur content of about .01 weight percent, a fluorine content not higher than about .002 weight percent, a clear CFR-R octane number of about 60 (slightly higher than that of the original charging stock), and a CFR-R octane number with 2 cc. of lead tetraethyl upwards of 73, which is appreciably higher than the corresponding octane number of the original charge. The gas oil boiling range product from the alumina treating step amounts to about 8 to 10 percent of the original charge and it has a sulfur content of about .17 and a negligible HF content.

After a run has been initiated, it is desirable to eliminate as much HF from the raffinate as possible before the raffinate is contacted with HF-activated alumina. We have found that the alumina is effective when it contains at least 10 to 15 weight percent of HF, but if the HF content of the alumina builds up to too great an extent, it may be necessary to eliminate HF from the catalyst. Although this may be done in the manner described, for example, in U. S. 2,397,085, we prefer to minimize the necessity of HF regeneration by removing as much as possible of the HF from the raffinate before the raffinate contacts the alumina. Defluorination may be effected by the use of alkalized alumina, as described in U. S. 2,391,149, but we prefer to effect the defluorination by heating and stripping in a raffinate-stripper defluorinator. The temperature of the defluorination in this defluorinator should be in the range of about 400 to 600° F., the pressure should be sufficient to prevent loss of all but the lightest naphtha components of the overhead stream and the use of an inert stripping gas such as propane or butane adds to the effectiveness of the defluorination.

The invention will be more clearly understood from the following description of a specific example thereof and by reference to the accompanying drawing which is a schematic flow diagram of a large scale plant for practicing the invention.

Coke still naphtha having a sulfur content of about .7 weight percent, a clear CFR-R octane number of 59.7 and an olefin content which exceeds its paraffin content was charged to a stirred reactor and contacted with 30 volume percent HF at about -20° F. for a period of approximately one-half hour. About 87.7 percent of the charge was separated as a raffinate and only about 12.3 percent was extracted, the extract after removal of HF being very high in sulfur

but suitable for blending in certain fuel oils. The raffinate contained about 53.4 percent, based on original charge, of components in the naphtha boiling range and this intermediate product naphtha fraction had a CFR-R octane number of only 38. The remainder of the raffinate, about 34.3 percent based on original charge, consisted essentially of polymers and alkymers of the gas oil boiling range.

Total raffinate in this case was neutralized and then contacted with activated alumina at about 750° to 800° F., under 400 pounds pressure, with a space velocity of about 1 and the product from the alumina contacting step was distilled into a 400° F. end point gasoline which was caustic washed and analyzed for sulfur and fluorine. The gasoline product amounted to 78.2 percent, based on initial charging stock, and it was characterized by a sulfur content of only .014, an HF content not exceeding .002 and a clear CFR-R octane number of 60.1. It is most remarkable that although the octane number of the naphtha portion of the original raffinate was only 38, that of the finished gasoline was 60.1. On a leaded basis, the improvement in octane number was even greater, the original naphtha with 2 cc. of lead tetraethyl having a CFR-R octane number of 69.6 and the product gasoline having a corresponding octane number of 73.3. It will be noted that the alumina treating of the HF raffinate increased the ultimate gasoline yield from 53.4 to 78.2 percent, an increase of about 25 percent, based on charge. The finished product had a sulfur content of only .014 percent, representing a 98 percent desulfurization. The octane number of the final gasoline and the lead response was better than that of the initial charge and the final gasoline was still highly olefinic.

Alumina activated by HF, as hereinabove described, was employed for effecting desulfurization of virgin West Texas heater oil boiling in the range of about 325° to 575° F. by treatment at a space velocity of about 1 and at a temperature of about 725° F., under 600 pounds hydrogen pressure. This heater oil initially contained about .6 percent sulfur and by this treating step 72 percent desulfurization was obtained while the same stock, when treated under the same conditions with alumina which contained no HF, gave only about 62 percent desulfurization. It will, thus, be seen that the HF-activated alumina which is produced in our process may be used for desulfurization of other charging stocks or for isomerization of olefins and then regenerated (U. S. 2,397,085) so that it may be subsequently used for treating additional HF raffinate.

Referring to the drawing, a coke still naphtha may be introduced by line 10 to extraction tower 11 into the top of which HF is introduced through line 12. The tower may be provided with baffles, trays, packing material, or the like and/or the naphtha may be introduced through atomizers or spray nozzles to insure thorough and intimate contact. Alternatively, of course, mixers and settlers may be employed such, for example, as are used for effecting sulfuric acid alkylation. The extraction may be at any pressure sufficiently high to maintain liquid phase conditions therein, the important feature being to maintain a temperature lower than would be employed for gas oil extraction and preferably in the range of about -60° F. to +30° F., the temperature in this particular case being -20° F. and about 30 volume percent HF being employed,

based on the naphtha charge, with a contact time of approximately one-half hour. The interface is preferably maintained at an intermediate or upper part of the tower.

The raffinate is removed overhead through line 13 to raffinate stripper-defluorinator 14 which is provided at its base with a heater or reboiler 15 and into which a stripping gas such as propane and/or butane is introduced through line 16. The stripper-defluorinator should be operated with a bottom temperature in the range of about 400° to 600° F., or approximately 500° F., and under a pressure sufficiently high and a top temperature sufficiently low to maintain most of the raffinate in the liquid phase. The top of the tower may be cooled or provided with reflux liquid (not shown). This heating and stripping not only removes dissolved HF from the raffinate but it decomposes most of the alkyl fluorides so that the raffinate removed through line 17 may contain only about .1 to .01 percent HF or less. During the start-up more HF may be allowed to remain in the raffinate in order to effect activation of the alumina as will be hereinafter described.

The extract phase withdrawn from tower 11 through line 18 is introduced into an extract stripper-defluorinator 19 provided with heater 20 which may operate under substantially the same conditions as stripper-defluorinator 14. HF-free extract is withdrawn from the base of stripper-defluorinator 19 through line 21 and although this extract may contain 2 to 6 percent of sulfur, it may be utilized as a blending stock for certain fuel oils.

The overhead stream from stripper 14 is withdrawn through line 22 and combined with the overhead stream from stripper 19 which is discharged through line 23, the combined streams being introduced by line 24 to HF recovery system 25. Since no invention is claimed in the particular means for separating H₂S, light hydrocarbons, and other contaminants from the HF in this system, it will not be described in detail. Systems for this purpose are illustrated in U. S. 2,532,492 and in copending application Serial Nos. 223,552 and 223,582, both filed on April 28, 1951. HF is recycled from the recovery system through line 22 along with make-up HF from line 26.

The substantially defluorinated raffinate withdrawn through line 17 is then passed through pipe still or heater 27 wherein it is heated to a temperature of about 800° F. and it is then introduced into converter 28, which in this case is packed with activated alumina. Although fixed bed contacting is described in this example, it should be understood that moving beds and fluidized solids systems may be used. Also, instead of the commercial grade of alumina known as activated alumina, we may employ alumina in other forms although the gamma alumina is preferred. Advantageous results may be obtained with ordinary calcined bauxite. Catalysts made from alumina gels are most advantageous and since they are well known for the manufacture of hydroforming catalysts, it is unnecessary to describe them in any further detail. While silica or metal oxides may be employed along with alumina, their presence is preferably in minor amount and a feature of our invention is the avoidance of any necessity of employing expensive cracking catalysts such as silica-alumina or reforming catalysts, such as molybdena-alumina or chromia-alumina.

The contacting in converter 28 may be effected in either gas phase or liquid phase condition although the latter is preferred. In other words, the contacting pressure is preferably superatmospheric and may be in the range of about 50 to 500 p. s. i. g. or more, at a temperature in the range of 600° F. to 900° F., preferably approximately 750° F. to 800° F. and with a space velocity in the range of about 1 to 3, preferably 1 to 1.5. In converter 28 residual alkyl fluorides are decomposed, the liberated HF being absorbed by the alumina to effect activation of said alumina. The HF-activated alumina is remarkably effective for depolymerizing and dealkylating the high boiling components of the raffinate while at the same time effecting further desulfurization and overall improvement of the octane number of the resulting gasoline-boiling range product. We prefer to maintain about 1 to 15 percent of HF on the alumina during the contacting step although activation is effected with even lesser amounts of HF and more HF than 15 percent may be tolerated. Coke deposition and gas formation are remarkably small in this operation which indicates that cracking in the usual sense occurs to only a very limited extent.

When the converter has been on stream for such period of time that it accumulates more than the desired amount of HF, the catalyst is preferably removed and utilized elsewhere, e. g. for desulfurizing heater oil or isomerizing olefins, and in either case it may thereafter be regenerated and/or defluorinated and used again for treating HF raffinate.

The product stream from converter 28 next passes by line 29 to fractionator 30 from which C₄ and lighter hydrocarbons may be taken overhead, a portion of them being condensed and returned to the tower as reflux and the remainder thereof being returned to line 16 to serve as a stripping medium in raffinate stripper-defluorinator 14. The light hydrocarbons from the overhead of fractionator 30 are highly olefinic in nature. A possible advantage to be realized by recycling them to stripper-defluorinator 14 is that part of these olefins may be polymerized or alkylated in the stripper by catalytic action of the HF present. Much of the polymer or alkylate will eventually be taken as an overhead product from fractionator 32, increasing not only the ultimate yield of gasoline but also its octane number. When this source of stripping gas is inadequate, light hydrocarbons from the HF recovery system 25 or saturated hydrocarbons from an outside source may be used as a stripping gas.

The bottoms from tower 30 are introduced by line 31 to fractionator 32 in which gasoline is taken overhead and heavier-than-gasoline materials are withdrawn as bottoms. For maximum gasoline production all or a part of the bottoms from tower 32 may be recycled to line 17 for passage through furnace 27 and through converter 28. Likewise, the high sulfur extract leaving tower 19 through line 21, after a hydrodesulfurization step, may be passed through furnace 27 and converter 28 for depolymerization and dealkylation to gasoline-boiling-range product. It will be understood that any known product fractionation system may be employed and that the above description is diagrammatic and by way of example.

From the above description it will be seen that we have attained the objects of our invention and have provided a process wherein about 98 percent desulfurization of coke still naphtha may

be effected while at the same time obtaining gasoline yields of approximately 78 to 80 percent, with about 12 percent of the original charge being removed as extract in the HF treating step and about 8 to 10 percent of the original charge being converted into heavier-than-gasoline hydrocarbons having a sulfur content of only about .17 weight percent. The resulting gasoline is highly olefinic and it is characterized by a higher octane number than the original charging stock and a much higher response to lead tetraethyl. While we have described a preferred example of our invention, it should be understood that the invention is not limited thereto since alternative procedural steps and operating conditions within the defined ranges will be apparent from the above description to those skilled in the art. Said description and drawing have been simplified for the purpose of clarity. It will be understood, of course, that heat exchangers, pumps, valves and safety precautions will be employed in accordance with known engineering standards and requirements.

We claim:

1. The method of desulfurizing a high sulfur olefinic naphtha, which method comprises intimately contacting said naphtha with hydrogen fluoride at a temperature in the range of -60° F. to +30° F. under conditions for obtaining a small amount of extract material containing a large amount of sulfur and for obtaining a large amount of raffinate, including polymers and alkymers of original charging stock components, removing most of the HF from said raffinate, then heating said raffinate to a temperature in the range of about 600° to 900° F. and contacting said raffinate at a temperature in said range with HF-activated alumina for effecting further desulfurization and a reconversion of most of the polymer and alkylate into hydrocarbons of the gasoline boiling range.

2. The method of claim 1 wherein the high sulfur olefinic naphtha is coke still naphtha.
3. The method of refining a high sulfur olefinic naphtha which method comprises contacting said naphtha with hydrogen fluoride at a temperature in the range of -60° F. to +30° F. with an amount of HF in the range of 5 to 200 volume percent and for a time of contact within the range of 6 to 60 minutes whereby extract and raffinate phases are formed, stripping said raffinate phase at a sufficiently high temperature to decompose most of the alkyl fluorides contained therein and to effect removal of liberated and dissolved HF therefrom, heating the stripped raffinate to a temperature in the range of about 600° to 900° F., contacting the heated raffinate at a temperature in said range with HF-activated alumina at a pressure in the range of about 50 to 500 p. s. i. g. and a space velocity in the range of .1 to 3 volumes of raffinate per hour per volume of HF-activated alumina and fractionating the products from the last-named contacting step to obtain a gasoline boiling range fraction which is olefinic and substantially free from sulfur and a small amount of a higher boiling hydrocarbon.
4. The method of claim 3 wherein the naphtha is a coke still naphtha.
5. The method of claim 3 wherein the naphtha contacting with HF-activated alumina is effected in liquid phase and wherein said alumina is associated with about 1 to 15 weight percent of HF.
